Inventor:
Percival John Purdy,
By his At't'y, W. Richards

UNITED STATES PATENT OFFICE.

PERCIVAL JOHN PURDY, OF LONDON, ENGLAND.

BOTTLE-LABELING MACHINE.

Application filed August 9, 1922. Serial No. 580,679.

To all whom it may concern:

Be it known that I, PERCIVAL JOHN PURDY, a subject of the King of Great Britain, residing in London, England, have 5 invented certain new and useful Improvements in Bottle-Labeling Machines, of which the following is a specification.

This invention relates to bottle labeling machines and refers to machines of the type 10 in which a vertically reciprocating picker is employed having surfaces to which gum is applied whereby a label may be removed from a magazine and brought into position for application to a bottle.

15 A vertically swinging arm is provided whereby the label is applied to and held on the bottle whilst the picker is withdrawn the application of the label being finally completed by vertically reciprocating wipers 20 which engage said label and press it down onto the bottle.

The present invention has for its object 25 to provide means which may be readily applied to existing machines whereby the back or inner surface of the label may have indicated upon it the date of labeling or any other particulars.

Printing mechanism according to this invention consists essentially of an arm or 30 lever carrying the type said arm being so mounted and operated as to enable it to swing from a position clear of the picker and other parts for effecting the labeling operation into a position such that the type 35 are caused to print upon the inner surface of the label. An inking device is provided for the type preferably so arranged that the type contacts therewith as the arm or lever moves into position to print upon the label.

40 According to one form of the invention there is provided upon some non-moving portion of the machine, conveniently upon the support for the label holder, an inking device. The device just referred to may 45 comprise a hollow roller designed to contain ink and having perforations through which the said ink may pass to an outer cover of some suitable material.

The type is carried by a horizontally 50 swinging arm which in one of its terminal positions contacts with the under-surface of the label in the label holder. Preferably

the type, which is in intaglio, or the holder therefor, is so mounted upon the said arm as to enable it to be adjusted longitudinally 55 thereof.

The arm just referred to is supported by two vertically disposed links connected at their lower ends respectively to the outer end of the arm and at a suitable point in 60 the length of the said arm the said links at their upper ends being pivotally supported by means of a bracket secured to some suitable portion of the machine. The second or inner link is so constructed or 65 supported at its upper end as to permit it at a certain point in its movement to move vertically upwards more or less in a straight line.

Secured to or operated by means of some 70 vertically reciprocating element of the machine is a vertically disposed rod supported in suitable guides and having adjustably secured to it a collar supporting a roller. Secured to the second or inner link of the type 75 carrying arm is a cam face or surface of such contour that the upward and downward movement of the rod will cause the said type carrying arm to move to and fro in the horizontal plane. The roller is caused to 80 contact with the aforesaid cam surface by spring pressure acting to cause the said surface to bear against the roller.

The upper end of the cam surface is provided with a projection with which the roller 85 contacts towards the end of its upward movement causing the end of the type carrying arm to move upwards and the type to impress the label.

In order that the invention may be the 90 better understood drawings are appended in which:—

Fig. 1 is a perspective view showing the 95 invention applied to a known type of machine.

Fig. 2 is a similar view with certain parts broken away to show the operating mechanism for the printing attachment.

Fig. 3 is a plan of the type carrying lever,

Fig. 4 is a side view to a larger scale illustrating certain details,

Fig. 5 is a longitudinal section of the inking roller.

Referring to the accompanying drawings

in which only such parts of the machine are identified as are necessary for the proper understanding of the invention, 1 indicates the main shaft of the machine, 2 the vertically reciprocating pickers having gum carrying surfaces whereby when raised into contact with the underside of the lowest label in the magazine 3 the said label adheres thereto and is drawn downwards ready for application to the bottle 4 to which it is applied and upon which it is held by the arm 5 whilst the pickers are withdrawn and the labeling operations are completed by the vertically reciprocating wipers 6.

15 Secured in any suitable manner to the frame of the label carrier, or supported therefrom in any suitable manner such as to permit of its horizontal and vertical adjustment, is a bracket 7 having slotted arms 20 in which are mounted, in a manner such that they are freely slideable therein, the journals of an inking cylinder or roller 8.

The downward movement of the roller is limited by the pins α , Fig. 5, passing transversely of the slots and one or both of which is or are removable so that the roller may be readily removed and replaced for filling with ink or other purposes.

The cylinder of the roller is provided with 30 an outer permeable cover 9 and is designed to contain ink for which purpose one of the ends thereof is removable. The cylinder is perforated to permit the passage of the ink to the outer cover 9.

35 Pivottally mounted at ω to a bracket 10^a secured to the main frame of the machine is a link 10 the lower end of which is secured to an arm 11 to the outer end of which is secured a type box 12, Fig. 3, carrying the type which is in intaglio. Preferably the type box or carrier is so mounted upon the arm as to permit of its adjustment lengthwise of said arm.

40 Pivottally mounted upon the bracket 10^a is a second link 13 slotted as shown for the passage of its pivot whereby, as will be presently more fully explained, the link has a limited longitudinal movement in addition to its swinging movement. A spring 14 is provided the tendency of which is to oppose the upward movement of the link. The lower end of link 13 is also pivottally connected to the aforesaid arm 11.

45 A vertically disposed rod 14^x has on its upper end a guide 15, the lower end of the rod passing through the horizontal member 16 of the machine and being connected to the vertically reciprocating wiper slide 17 supported by the rod 18 indicated by dotted lines in Fig. 2.

50 The rod 14^x has secured to it a collar 18^x carrying a roller 19 engaging a cam surface 19^a of the link 13^a whereby as the rod moves upwards the link 13 is caused to swing forward and the type to pass over the inking

roller which roller, as previously explained, is so mounted that it is free to rise and fall vertically in its support whereby it may yield to the pressure of the type at the same time being caused to apply the ink thereto. 70

When, however, the rod is approaching its limit of upward motion the roller 19 contacts with the upper end of the cam surface whereby the arm 11 has imparted to it a direct upward movement causing the type to print upon the label. The return of the arm is assisted by the spring 14 before referred to. 75

Claims:

1. In a bottle labeling machine, the combination of, a swinging member; means upon said member adapted for impressing characters upon the backs of labels while the labels are in the machine; and means for operating said member; said member having a straight line movement and a direct vertical movement. 80

2. In a bottle labeling machine, the combination of, a swinging member; means upon said member adapted for impressing characters upon the backs of labels while the labels are in the machine; and means for operating said member; said member having a straight line movement towards and away from the backs of the labels. 90

3. In a bottle labeling machine, the combination of, a swinging member; intaglio type upon said member for impressing characters upon the backs of labels while the labels are in the machine; and means for operating said member; said member having a straight line movement towards and away from the backs of the labels. 95

4. In a bottle labeling device in combination, a label magazine, vertically reciprocating gumming devices for applying an adhesive at the sides of said label and removing it from the magazine, means for applying it to the bottle, means for printing upon the label, comprising an arm, intaglio type upon said arm, links connected to said arm, a cam surface upon one of said links, a vertically reciprocating member engaging said cam surface, a stop engaged by the member at the end of its upward travel whereby said arm has imparted to it a direct upward movement and an inking device arranged in the path of movement of the type. 100

5. In a bottle labeling device in combination, a label magazine, vertically reciprocating gumming devices for applying an adhesive at the sides of said label and removing it from the magazine, means for applying it to the bottle, means for printing upon the label comprising an arm, intaglio type upon said arm, links connected to said arm, one of said links being capable of longitudinal movement and the other of said links having a cam surface, a vertically reciprocating member engaging said cam surface, a 110

stop engaged by the body at the end of its upward travel whereby said arm has imparted to it a direct upward movement, and an inking device arranged in the path of 5 movement of the type.

6. In a bottle labeling device in combination, a label magazine, vertically reciprocating gumming devices for applying an adhesive at the sides of said label and removing it from the magazine, means for applying it to the bottle, means for printing upon the label comprising an arm, intaglio type upon said arm, links connected to said arm, one of said links having a slot in the end 10 thereof, a pivot engaging said slot, a spring opposing the longitudinal movement of said link, a cam surface upon one of said links, a vertically reciprocating member engaging said cam surface, a stop engaged by said member at the end of its upward travel 15 whereby said arm has imparted to it a direct upward movement, and an inking device arranged in the path of movement of the type.

25 7. In a bottle labeling device in combination, a label magazine, vertically reciprocating gumming devices for applying an adhesive at the sides of said label and removing it from the magazine, means for applying it to the bottle, means for printing upon the label comprising an arm, intaglio type upon said arm, a bracket upon the frame of the machine, a link pivotally mounted upon said bracket and connected 30 to the outer end of said arm, a second link pivotally mounted upon said bracket and connected to said arm, a slot in the second link, a spring interposed between the pivot of the second link and the end of the slot, a 35 cam surface on the second link, a vertically reciprocating rod, a roller upon said rod engaging said cam surface to swing said link, and an inking device arranged in the path of movement of the type.

45 8. In a bottle labeling machine in combination, a label magazine, vertically reciprocating gumming devices for applying an adhesive at the sides of said label and removing it from the magazine, means for applying it to the bottle, means for printing upon the label comprising an arm, intaglio type upon said arm, a bracket upon the frame of the machine, a link pivotally mounted upon said bracket and connected to 50 the outer end of said arm, a second link pivotally mounted upon said bracket and connected to said arm, a slot in the second link, a spring interposed between the pivot of the second link and the end of the slot, a 55 curved slot running longitudinally of the second link on the second link, a vertically reciprocating rod, a roller upon said rod engaging said slot and contacting with the upper end thereof to lift said link against

the action of said spring, an inking device 65 arranged in the path of movement of the type, said inking device comprising a hollow roller, perforations in said roller, an outer absorbent cover for said roller with which the type contacts in its passage to 70 the label.

9. In a bottle labeling machine in combination, a label magazine, vertically reciprocating gumming devices for applying an adhesive at the sides of said label and removing it from the magazine, means for applying it to the bottle, means for printing upon the label comprising an arm, intaglio type upon said arm, a bracket upon 75 the frame of the machine, a link pivotally mounted upon said bracket and connected to the outer end of said arm, a second link pivotally mounted upon said bracket and connected to said arm, a slot in the second link, a spring interposed between the pivot of the second link and the end of the slot, a curved slot running longitudinally of the second link on the second link, a vertically reciprocating rod, a roller upon said rod 80 engaging said slot and contacting with the upper end thereof, an inking device arranged in the path of movement of the type, said inking device comprising a hollow roller, perforations in said roller, ends to 85 said roller one of which is removable for the introduction of the ink, pivots for the support of said roller, a bracket for said roller, slots in said bracket to receive the pivots, said pivots being freely movable in said slots to permit the roller to rise and fall, an outer absorbent covering for said roller with which the type contacts in its passage to the label.

10. In a bottle labeling machine in combination, a label magazine, vertically reciprocating gumming devices for applying an adhesive at the sides of said label and removing it from the magazine, means for applying it to the bottle, means for printing upon the label comprising an arm, intaglio type upon said arm, a bracket upon the frame of the machine, a link pivotally mounted upon said bracket and connected to the outer end of said arm, a second link pivotally mounted upon said bracket and connected to said arm, a slot in the second link, a spring interposed between the pivot of the second link and the end of the slot, a curved slot running longitudinally of the second link on the second link, a vertically reciprocating rod, a roller upon said rod 105 engaging said slot and contacting with the upper end thereof, an inking device arranged in the path of movement of the type, said inking device comprising a hollow roller, perforations in said roller, a plug filling one end of said roller, a central projection of said plug forming a pivot for the 110 115 120 125

roller, a milled head upon said pin, a closure for the other end of said roller, a pivot upon said end, a bracket for said roller, slots in said bracket to receive the pivots, said pivots being freely movable in said slots to permit the roller to rise and fall, an absorbent covering for said roller with which

the type contacts in its passage to the label.

In testimony whereof I have hereunto set my hand in the presence of two witnesses.

PERCIVAL JOHN PURDY.
